UNITED STATES PATENT OFFICE.

EDWIN M. CORYELL, OF BROOKLYN, NEW YORK, ASSIGNOR TO THOMAS FORKNALL, OF SAME PLACE.

OSCILLATING PRINTING-PRESS.

SPECIFICATION forming part of Letters Patent No. 229,675, dated July 6, 1880.

Application filed March 2, 1880. (Model.)

To all whom it may concern:

Be it known that I, EDWIN M. CORYELL, a resident of Brooklyn, in the county of Kings, in the State of New York, have invented a new, useful, and important Improvement in 5 Printing-Presses, described in this specification.

My invention consists, principally, of an arm having a slot to move in contact with a fixed 10 bearing, and operating mechanism to give the requisite period of motion and rest to the platen and afford ample time to feed the press and secure a good impression.

Figure 1 is a perspective view of one form of 15 press involving my invention. Fig. 2 is a longitudinal vertical middle section, and Fig. 3 a rear vertical view of the same.

In this form of press, A A are side frames, supported by cross-bars a b c d. B is a driving-shaft, to which motion may be imparted 20 by crank, treadle, pulley, or gear, to suit the power to be employed. C is a pinion on the driving-shaft. D is a gear-wheel into which the pinion meshes. G is a pitman connecting the crank and the arms H I of the toggle-joint at h.

The arm H is supported on its outer end on cross-bar c. The arm I has a slot, m, through 30 which passes the cross-bar d, having a roller, n, to fit the slot.

O is a cross-bar passing through the slotted arm at k, and connecting the arms q r to the platen-support S, which is supported on cross-bar t, and to which the platen N is adjustably 35 connected. V is a bed secured to the side frames.

When motion is communicated to the press the toggle-joint is operated, and, in consequence of the peculiarly-shaped slot m and the roller n, a peculiar motion is imparted to the 40 cross-bar O, arms q r, and platen N, by which the platen is raised and lowered and rests, when down and when up, to afford ample time to feed the press and to secure a good impression.

Changes may be made in the construction 45 and operation of the press within the scope of my invention.

I claim as my invention—

1. The combination of platen N, bed V, arms 50 q r, bar O, toggle-arms H I, the latter having guide m, bar d, having roller n, pitman G, crank-shaft B, gear-wheel D, pinion C, driving-shaft B, and frame A, substantially as described.

2. The combination of platen N, arms q r, bar O, toggle-arms H I, the latter having guide m, bar d, having roller n, and operating mechanism, substantially as described.

3. The combination of a platen, a toggle-joint one arm of which has a guide, substantially as described, a bearing for the guide, and intermediate and operating mechanism, substantially as described.

In testimony whereof I hereunto subscribe 65 my signature and affix my seal, in the presence of two attesting witnesses, on the 23d day of February, 1880.

EDWIN M. CORYELL. [L. S.]
